UNITED STATES PATENT OFFICE.

FRANK BASCH, OF COLUMBUS, OHIO.

MACHINE FOR CUTTING AND RIPPING SEAMS.

SPECIFICATION forming part of Letters Patent No. 271,019, dated January 23, 1883.

Application filed November 15, 1882. (No model.)

To all whom it may concern:

Be it known that I, FRANK BASCH, of Columbus, in the county of Franklin and State of

Ohio, have invented certain new and useful 5 Improvements in Machines for Cutting the Seams in Old Garments; and I do hereby declare the following to be a full, clear, and exact description of the invention, such as will enable others skilled in the art to which it pertains to make and use it, reference being had to the accompanying drawings, which form part of this specification.

My invention relates to an improvement in machines for cutting and ripping seams, to be 10 used in the manufacture of shoddy; and it consists in the combination of a pair of shears or other similar cutting device, which is secured to the edge of the table, with a lever which is attached to or formed upon one of 15 the jaws of the shears, a connecting-rod which is attached at its lower end to a treadle, and a connecting-rod which connects the treadle or operating-lever with the driving wheel or shaft, as will be more fully described herein-after.

The object of my invention is to provide a machine by means of which the seams in old garments that are to be used in the manufacture of shoddy can be ripped, and by which 20 the lining, which is usually sewed in the seams, can be removed much more easily and rapidly than can be done by hand.

Figure 1 is a side elevation of my invention. Fig. 2 is an end view of the same.

35 A represents a suitable frame or table, to one edge of which is secured the jaw B of the shears. This jaw B is secured to the edge of the table by having a suitable projection, C, secured on the edge of the table for the hole 40 in the end of the handle to catch over, and a screw or bolt is then passed through the cutting end of the jaw into the table. In this position the jaw is rigidly held in a line parallel with the edge of the table, and either in 45 close contact therewith or moved outward from it to any suitable distance. The second jaw, F, is pivoted upon the stationary jaw, and has its inner end extending beyond the end of the stationary jaw a suitable distance; or 50 this jaw may have a lever, G, secured to it for the purpose of obtaining a greater leverage.

To the outer end of this lever G is pivoted the connecting-rod H, which rod has its lower end loosely connected to the outer end of the treadle I. This treadle I is journaled upon 55 the rod J, which extends lengthwise of the machine, and which treadle is operated by means of the connecting-rod L, which is fastened at its upper end to the wrist-pin upon the driving or balance wheel P. By making this 60 wrist-pin adjustable in the wheel a longer or shorter stroke can be given to the shears, as may be preferred. The treadle may be operated either by means of power or by foot; but in either case the fly-wheel will be given a 65 continuous rotary motion, so as to give the shears a steady and even cut.

The garments to be deseamed have the 70 seams drawn over the stationary jaw of the shears, and the movable jaw then descends and cuts the thread and seams from the garments, and at the same time releases the lining which is sewed in the seams.

By means of the construction above described old garments which are to be prepared for the manufacture of shoddy can be 75 ripped and deseamed with great ease and rapidity, as compared with the slow method of cutting the seams with hand-shears.

The movable jaw of the shears is prevented 80 from springing by means of a guide-rod, R, which is secured to the table, and which bears against the outer side of the jaw the entire length of its stroke.

Having thus described my invention, I 85 claim—

1. The combination of a suitable frame, the jaw B, rigidly secured thereto, the pivoted jaw having the lever G, connecting-rod H, treadle I, and a rod for connecting the treadle 90 with the driving or balance wheel, substantially as shown and described.

2. The combination of the guard R with the stationary jaw B, pivoted jaw F, and the operating mechanism, substantially as set forth. 95

In testimony whereof I affix my signature in presence of two witnesses.

FRANK BASCH.
